No. 37,318.

Patented February 7, 1905.

UNITED STATES PATENT OFFICE.

LOUIS BEDICHIMER, OF PHILADELPHIA, PENNSYLVANIA, ASSIGNOR TO J. GURNEY TAYLOR, OF PHILADELPHIA, PENNSYLVANIA, GRAND CORRESPONDENCE SECRETARY IN TRUST FOR THE GRAND CHAPTER ALPHA MU PI OMEGA MEDICAL FRATERNITY.

DESIGN FOR A BADGE.

SPECIFICATION forming part of Design No. 37,318, dated February 7, 1905.

Application filed January 12, 1905. Serial No. 240,833. Term of patent 14 years.

To all whom it may concern:

Be it known that I, LOUIS BEDICHIMER, a citizen of the United States, residing in the city and county of Philadelphia, State of Pennsylvania, have invented a new, original, and ornamental Design for a Badge, reference being had to the accompanying drawing, forming part thereof, and which is a face view of the design.

What I claim as new, and desire to secure by Letters Patent, is—

The ornamental design for a badge substantially as shown.

LOUIS BEDICHIMER.
